L. KASSANDER.

LUBRICATOR.

APPLICATION FILED JULY 14, 1921.

1,425,972.

Patented Aug. 15, 1922.

Leopold Kassander Inventor

By his Attorney

Clarence G. Campbell

UNITED STATES PATENT OFFICE.

LEOPOLD KASSANDER, OF NEW YORK, N. Y., ASSIGNOR TO NATHAN MANUFACTURING COMPANY, OF NEW YORK, N. Y., A CORPORATION OF NEW YORK.

LUBRICATOR.

1,425,972.

Specification of Letters Patent. Patented Aug. 15, 1922.

Application filed July 14, 1921. Serial No. 484,526.

To all whom it may concern:

Be it known that I, LEOPOLD KASSANDER, a citizen of the United States, residing at 236 West 70th St., in the borough of Manhattan, in the county of New York, city and State of New York, have invented certain new and useful Improvements in Lubricators, of which the following is a specification.

10 My invention relates to lubricators adapted to be used in lubricating moving parts having impulsive or vibrating action, and the novelty consists in the adaptation and arrangement of the parts, as hereinafter 15 fully set forth.

Figure 1 is a front elevation of my device with the lower portion broken away to show the valve construction. Figure 2 is a vertical section of the housing and connecting 20 parts of my device showing the internal parts uncut.

25 In the drawings 3 is an oil reservoir which has a hollow central stem 4, and also has internally threaded borings 5 adapted to be used when securing said reservoir 3 and its connecting parts by means of screws 6 to a bracket 7 or other suitable place in a locomotive, or wherever it is desired. A cap 8 is adapted to be screwed down over the external threading 9 at the head of the central stem 4. The hollow central stem 4 is internally threaded at 10, and near the head of the stem 4 is a larger boring 11 which is internally threaded.

30 35 A regulating spindle 12, which is externally threaded at its head portion has a slot 13 and is adapted to be screwed into the internal threading 10 until a needle point 14 at the lower end of the spindle 12 is adjusted 40 to the position desired. A plug 15 is adapted to be screwed into the internally threaded boring 11, so as to lock the spindle 12 in a fixed position against change from vibration after adjustment.

45 The stem 4 is bored at 16 so as to permit the oil to pass from the reservoir 3 into the hollow opening in the stem 4. The hollow opening of the stem 4 tapers to a small passageway 17. A tubular boring 18 is also 50 made in the stem 4 parallel with the hollow opening, which ends at its base in a narrow passageway 19.

55 The base of the oil reservoir 3 has an internally threaded boring 20 into which is adapted to be screwed the externally

threaded neck 21 of a two chamber member 22 which has an upper chamber 23, which is connected to a lower chamber 24 by means of a tubular opening 25. The upper chamber 23 has a tapered valve seat 26 at its base, 6 and the lower chamber 24 has an enlarged portion 27 at its base tapering up in a valve seat 28 to the upper portion of the chamber 24. A valve stem 29 carrying a valve 30 at its head is adapted to be screwed into a 6 lower valve 31, thereby rigidly connecting the upper valve 30 to the lower valve 31, so that when the valve 30 is seated on the valve seat 26 the valve 31 is unseated from the valve seat 28, and when the valve 31 is seated on the valve seat 28 the valve 30 is unseated from the valve seat 26. The valve 30 has flattened portions 33 on the side of the circular surface of the same, and the valve 31 has flattened portions 32 on the side of the 7 circular surface, so that there are always open spaces between the circular heads of said valves.

8 The two chamber member 22 is internally threaded at the lower end 34, and a cap 35 which is externally threaded at 36 is adapted to be screwed into the internal threading 34, thereby closing the lower chamber 24. In the base of the internally threaded boring 20 is an annular groove 47 8 which runs through the narrow passageway 19, and a narrow passageway 46 is made in the two chamber member 22, so that it will also connect with the annular groove 47. In this way whatever position the narrow 9 passageway 46 may be in when the two chamber member 22 is threaded into the internally threaded boring 20 it will always connect with the annular groove 47, and through said annular groove 47 it will then connect through the narrow passageway 19, and thence through 18 to the top of the oil reservoir 3.

10 The cap 35 has an internal boring which is threaded at 37, and this boring 37 is connected to the chamber 27 by means of a series of small passages 38. The internally threaded boring 37 is adapted to be used for making the necessary connection to the air pump or other device to which the 1 lubricator may be attached.

11 The cap 8 has a boring which is internally threaded at 39, and into which a plug 40 having external threading 41 is adapted to be screwed, said boring 39 being 1

adapted to be used as a filler for the oil reservoir 3. The plug 40 has a nipple 42 extending from the bottom over which a chain 43 is secured, and said chain 43 has a large ring 44 which is larger than the opening 37, and thereby adapted to retain the plug 40 in a suspended position ready for replacing whenever it is removed from the cap 8 in order to fill the oil reservoir 3. A strainer 45 of usual construction is mounted in the oil reservoir 3 to prevent any dirt or foreign substance from going through the valves into the mechanism to be lubricated from the oil reservoir 3. The oil reservoir 3 is filled with oil by removing the plug 40 from the cap 8 and replacing the same in the threaded boring 39. The oil will pass through the boring 16, and by the needle valve 14 into the narrow passage 17, and thence into the upper valve chamber 23 which is opened when the air pump to which this lubricator is adapted to be secured is on the pressure stroke. This permits the oil to pass through the tubular opening 25 into the lower chamber 24. The positions of valves 30 and 31 during this operation are shown in Figure 1. While the valve 30 is on its upward movement as described a slight amount of air will pass by this valve and through the passages 25, 23, 17, 16, 46, 19, and 18 to the top of the oil reservoir, creating a slight pressure and preventing a formation of a partial vacuum which may interfere with the steady and regular operation of the device. While the valve 31 is thus held on its seat 28 a certain amount of oil is permitted by the position of the needle valve 14 to trickle down through the narrow opening 17 into the upper chamber 23, thence through the tubular opening 25 into the lower chamber 24. When the piston of the air pump reverses the motion and is on the suction stroke the valve 31 drops away from its seat 28 and the valve 30 closes. The oil which has collected in the chamber 24 will then be drawn out of the chamber 24 past the valve 31 and through the small passages 38 into the larger passage or boring 37, thence into the pipes connecting with the air pump or other part to be lubricated. When the device is regulated so that the oil flows past the needle valve 14 at the desired rate required by the service the operation is automatic and is the result of the alternate and pulsating action of the air pump or other device to which the lubricator may be attached.

I claim:

1. In a lubricator the combination of an oil reservoir, adjustable means of regulating the flow of oil from said reservoir into a two chamber member connected to said reservoir, a downwardly seating valve in the upper chamber, and an upwardly seating valve in

the lower chamber, said valves being rigidly connected by a stem, together with additional means of venting air from said chamber to the top of said oil reservoir consisting of a passage from said chamber and from said oil reservoir to an annular groove common to each.

2. In a lubricator the combination of an oil reservoir having a hollow central stem in which is adjustably mounted a regulating spindle, and means for locking the same in place, a two chamber member connected to said reservoir, a downwardly seating valve in the upper chamber and an upwardly seating valve in the lower chamber, said valves being rigidly connected by a stem, together with additional means of venting air from said chamber to the top of said oil reservoir consisting of a passage from said chamber and from said oil reservoir to an annular groove common to each.

3. In a lubricator the combination of an oil reservoir, adjustable means of regulating the flow of oil from said reservoir into a two chamber member connected to said reservoir, a downwardly seating valve in the upper chamber, and an upwardly seating valve in the lower chamber, said valves being rigidly connected by a stem and a lower cap member, having small passages therethrough adapted to close said two chamber member and furnish a connection to the part to be lubricated.

4. In a lubricator the combination of an oil reservoir, adjustable means of regulating the flow of oil from said reservoir into a two chamber member connected to said reservoir, a downwardly seating valve in the upper chamber, and an upwardly seating valve in the lower chamber, said valves being rigidly connected by a stem, together with additional means of venting air from said chamber to the top of said oil reservoir, and a lower cap member, having small passages therethrough adapted to close said two chamber member and furnish a connection to the part to be lubricated.

5. In a lubricator the combination of an oil reservoir, adjustable means of regulating the flow of oil from said reservoir into a two chamber member connected to said reservoir, a downwardly seating valve in the upper chamber, and an upwardly seating valve in the lower chamber, said valves being rigidly connected by a stem, together with additional means of venting air from said chamber to the top of said oil reservoir consisting of a passage from said chamber and from said oil reservoir to an annular groove common to each and a lower cap member, having small passages therethrough adapted to close said two chamber member and furnish a connection to the part to be lubricated.

6. In a lubricator the combination of an oil reservoir having a hollow central stem

in which is adjustably mounted a regulating spindle, and means for locking the same in place, a two chamber member connected to said reservoir, a downwardly seating 5 valve in the upper chamber and an upwardly seating valve in the lower chamber, said valves being rigidly connected by a stem, together with additional means of venting air from said chamber to the top of said oil reservoir consisting of a passage from said 10 chamber and from said oil reservoir to an

annular groove common to each, and a lower cap member, having small passages therethrough adapted to close said two chamber member and furnish a connection to the part 15 to be lubricated.

In testimony whereof I affix my signature in presence of two witnesses.

LEOPOLD KASSANDER.
